[57] **CLAIM**

The ornamental design for a tire, as shown and described.

DESCRIPTION

FIG. 1 is a side elevational view of a tire showing our new design with a portion thereof cut away for ease of disclosure, it being understood that the structure continues uniformly throughout the circumference of the tire;

FIG. 2 is a front elevational view thereof, it being understood that the tread pattern continues uniformly throughout the circumference of the tire;

FIG. 3 is a side elevational view thereof, the opposite side elevational view being identical thereto;

FIG. 4 is a cross-sectional view thereof, taken on line 4—4 of FIG. 3;

FIG. 5 is a side elevational view of a second embodiment of a tire showing our new design with a portion thereof cut away for ease of disclosure, it being understood that the structure continues uniformly throughout the circumference of the tire;

FIG. 6 is a front elevational view thereof, it being understood that the tread pattern continues uniformly throughout the circumference of the tire;

FIG. 7 is a side elevational view thereof, the opposite side elevational view being identical thereto; and,

FIG. 8 is a cross-sectional view thereof, taken on line 8—8 of FIG. 7.
